DESIGN FOR A BICYCLE FRAME

Herman L. Kraeft, Cleveland Heights, Ohio, assignor to The Murray-Ohio Manufacturing Company, Cleveland, Ohio, a corporation of Ohio

Application August 10, 1936, Serial No. 64,331

Term of patent 7 years

To whom it may concern:

Be it known that I, Herman L. Kraeft, a citizen of the United States, residing at Cleveland Heights, in the county of Cuyahoga and State of Ohio, have invented a new, original, and ornamental Design for a Bicycle Frame, of which the following is a specification, reference being had to the accompanying drawing, forming a part thereof.

In the drawing, Fig. 1 is a side elevation of a bicycle frame showing my new design; Fig. 2

is a section through the frame, as indicated by the lines 2—2 on Fig. 1; Fig. 3 is a perspective view of the frame.

The dominant features of the design are those shaded by stippling, particular reference being directed to the shape of the rear fork members, especially at their points of connection.

I claim:

The ornamental design for a bicycle frame substantially as shown and described.

HERMAN L. KRAEFT.
